Application May 16, 1939, Serial No. 273,954

22 Claims. (Cl. 242—53)

This invention relates to improved means for adjusting the inclination of two parts, such as two rotating parts, with respect to each other.

The invention may advantageously be employed in connection with the adjustment of the angle of inclination between the axes of rotation of two rotating parts the axis of each of which parts is contained within the periphery of the other part. Thus the invention may be employed to particular advantage in connection with reels for advancing strand material, such as thread, comprising interdigitating sets of bar members having supporting means which during operation of the reel rotate about axes which are inclined to each other and in which reel the axis of the supporting means for each set of bar members is contained within the periphery of the other set. By providing improved means for adjusting the inclination of the axes of rotation of said supporting means, the present invention makes it possible to adjust the pitch of the helical turns of thread wound on the reel.

For convenience, but in no sense of limitation, the invention will be described in connection with a reel of such type operating on the principle of that shown and described in British Patent No. 413,414. Said reel comprises two wholly rigid sets of bar members, each set being of substantially circular cross section and rotatable as a whole about an independent axis displaced from that of the other set. Preferably the axes of rotation of said sets of bar members are disposed in inclined relation in parallel planes which are slightly spaced from each other, since with this relation of the axes the most efficient advance of the thread is obtained.

In such a reel, the reel advances the thread lengthwise thereof in a plurality of spaced, generally helical turns during rotation of the sets of bar members about their axes. The offset relationship of the axes causes each thread turn to be carried by the bar members of both sets and to be transferred from the bar members of each set to those of the other during the rotation of the reel, certain of the bar members of each set being retracted within the periphery defined by such thread-carrying bar members of the other set. The inclined relation of the axes causes the thread to advance.

It is desirable, under certain conditions, that the angle between the axes of rotation of the sets of bar members be adjustable, since in this manner the pitch or spacing of the helical thread turns on the reel, and consequently the length of thread stored on the reel, can be varied. This

is particularly desirable in the continuous processing of thread wherein the thread is subjected to one or more processing treatments while being continuously but temporarily stored on the reel, since the time of processing of the thread can be adjusted without changing the speed of rotation of the reel by suitably changing the length of thread stored on the reel. Moreover, it is also often desirable that the pitch of the helical turns stored on the reel be capable of adjustment when it is desired to employ the reel to wind material of different widths on the reel.

It is also a desideratum that any variation in the angle of inclination between the axes of rotation of the reel members be accomplished without varying the amount of offset between such axes; i. e., without moving the axes out of their spaced, parallel planes when they are adjusted relatively to each other.

For instance, if delicate material, such as artificial silk thread, is being subjected to liquid processing treatment while stored on such a reel, and particularly if it is being processed under conditions such that a film of processing liquid is formed which extends for a substantial distance lengthwise of and entirely around the reel, the amount of offset between the axes of the sets of bar members is critical. It has been found that the offset should not be so large that the retracting bar members of each set can withdraw sufficiently within the periphery defined by the thread-carrying bar members of the other set to cause the film of processing liquid formed between such retracted bar members and the thread turns to break. The abrupt snapping of the breaking film will disarrange the turns of thread or the filaments thereof, causing entangling and subsequent breakage of such turns when they are subsequently un wound from the reel.

The retracted bar members should, however, be withdrawn sufficiently so that they cannot influence the thread turns carried by the projecting bar members of the other reel member; otherwise, they push adjacent thread turns together and cause entangling thereof. A slight increase or decrease in the amount of offset between the axes of rotation of the sets of bar members may, under such conditions, cause great difficulties. Consequently, in reels employed as described immediately above, if the amount of inclination between the axes of rotation of the sets of bar members is adjustable, the adjustment preferably should not result in a change in the amount of offset.

It has been found desirable in commercial practice to employ reels of cantilever construction; i. e., reels which are supported from one end only and have the other end unobstructed. In this manner, great advantages in connection with the threading up of the reels and in respect of the accessibility thereto are provided. However, in commercial practice large numbers of reels are employed on a single machine, being disposed close together. Therefore the adjusting means must, because of space limitations, be extremely compact in structure and easily operated.

The present invention provides simple and efficient adjusting means which can satisfy all of the above requirements.

In the drawings, in which are illustrated two different embodiments of the invention, Figure 1 is a plan elevation from line 1—1 of Figure 3 of a reel constructed in accordance with one of said embodiments, said reel operating on the principle of the reel shown and described in the above-mentioned British Patent No. 413,414. Figure 2 is a sectional elevation of said reel from line 2—2 of Figure 3. Figure 3 is a corresponding end elevation of said reel from line 3—3 of Figure 2.

Figure 4 is a plan on an enlarged scale of the adjusting means of the embodiment of Figures 1 to 3, inclusive, the reel members being removed and parts shown in section for the sake of clearness. Figure 5 is a sectional side elevation, parts being broken away, of the adjustment means of Figure 4. Figure 6 is an end elevation of said adjustment means from line 6—6 of Figure 5. Figure 7 is a sectional elevation of said adjustment means from line 7—7 of Figure 5. Figures 4 to 7, inclusive, show but exaggerate somewhat the maximum inclined relation of the axes of rotation of the reel members, the same being the relationship shown in Figures 1 to 3, inclusive.

Figures 8 to 11, inclusive, are similar elevations on the same enlarged scale of the same adjusting means but show the relationship of the parts for a somewhat smaller angle of inclination between the axes of rotation of the reel members. Figure 8 represents a sectional plan from line 8—8 of Figure 10. Figure 9 represents a sectional elevation from line 9—9 of Figure 10. Figure 10 represents an end elevation of the adjustment means from line 10—10 of Figure 9. Figure 11 represents a sectional elevation from line 11—11 of Figure 9.

Figures 12 to 15, inclusive, are similar elevations on the same scale of said adjustment means, but show the relationship of the parts when the axes of rotation of the reel members are adjusted into parallel relationship in a common plane so that, on the illustrated reel, no advance of the thread takes place. Figure 12 represents a plan with parts broken away. Figure 13 represents a sectional side elevation with parts broken away. Figure 14 represents an end elevation from line 14—14 of Figure 13. Figure 15 represents a sectional elevation from line 15—15 of Figure 13.

Figures 16 to 19, inclusive, are elevations similar to those described above and on the same scale showing the relationship of the parts for an opposite angle of inclination of the axes of rotation of the reel members; so that, for the same direction of rotation, a travel of the thread in the direction opposite to that for the positions described above results. In this group, Figure 16 represents a sectional plan from line 16—16 of Figure 18. Figure 17 represents a longitudinal

sectional elevation from line 17—17 of Figure 18. Figure 18 represents an end elevation of the adjustment means from line 18—18 of Figure 17. Figure 19 represents a sectional elevation of the adjustment means from line 19—19 of Figure 17.

Figure 20 is a plan elevation of a reel operating on the same principle as that of Figures 1 to 3, inclusive, and to the same scale thereof, but embodying another form of the present invention. 10 Figure 21 is a sectional elevation of said reel from line 21—21 of Figure 20. Figure 22 is a sectional elevation through the adjustment means of said reel from line 22—22 of Figure 21.

In Figures 20 to 22, inclusive, as also in Figures 15 to 19, inclusive, like reference characters refer to like parts.

The reel illustrated in Figures 1 to 3, inclusive, as embodying the invention is of cantilever form, being supported from one end only and having 20 its other end unsupported. It comprises two rigid reel members 1 and 2, each of said reel members being generally circular in cross section and including a set of spaced bar members which extend longitudinally of the reel. The bar 25 members of each reel member are interleaved with those of the other reel member, as shown in Figure 3. Each reel member is mounted for individual rotation about an axis inclined to that of the other reel member.

30 The bar members 3 of reel member 1 are formed integrally with a cylindrical body portion 4. The latter includes a hub portion by means of which reel member 1 is concentrically mounted on shaft 5 for driving relation therewith. Shaft 5 is journaled in frame member 6, rigidly supported from one end only thereof. Because of the manner in which it is mounted on shaft 5, reel member 1 may be termed the concentric reel member.

Reel member 1 is held by a cup nut 8 threaded 40 on the end of the drive shaft 5 against a collar 7 mounted on the shaft. The collar 7, in addition to serving as means against which the concentric reel member 1 can bear, also serves to locate the shaft 5 endwise in the frame member 6. A pin 9 passes through drive shaft 5 and has its projecting ends disposed in a slot 11 in the hub member of the concentric reel member, thus providing positive driving engagement of said reel member 1 with said drive shaft 5.

50 The other reel member 2 is mounted on frame member 6 for rotation about an axis which is displaced from the axis of rotation of the concentric reel member, wherefore said reel member 2 may be termed the eccentric reel member. In the 55 illustrated embodiment of the invention, it embodies a supporting member 12 by means of which it is rotatably mounted on frame member 6. Supporting member 12 has rigidly mounted thereon a metallic sleeve 13 which serves as the bearing surface. In addition, supporting member 12 serves to carry a rigid cage-like member 14 embodying a set of spaced longitudinally extending bar members 15 which are interleaved with the bar members 3 of the concentric reel member 1.

65 Cage-like member 14 is preferably of one piece cast or molded construction, having formed integrally therewith at the end thereof adjacent the unsupported end of the reel an annular ring 16 fixed to the inner portions of bar members 15. Formed integrally therewith at the other end of cage-like member 14 is an external annular ring 17 fixed to the outer portions of the bar members 15. Said external annular ring 17 serves as the means by which said cage member 14 is mounted 70 on the supporting member 12, as by the bolts 18.

in the illustrated embodiment of the invention.

If the reel is to be employed in the processing of thread, as by means of processing liquid applied to the thread on the reel, it is desirable that it be so constructed that it is not attacked by the processing agents. For this reason, the space between the concentric and eccentric reel members is closed off by a suitable seal 19 which may be formed of flexible reagent resistant material such as rubber, being clamped to the hub portion of the concentric reel member 1 as by spring ring 21 and having its other edge clamped in the eccentric member. In the apparatus shown, the outer edge of the seal 19 is provided with a plurality of ridges 22 which are clamped between the supporting member 12 and a suitable washer 23 formed of reagent resistant material, the washer being urged against said ridges 22 by shoulders 24 formed on the inner surfaces of the bar members 15 of eccentric reel member 2. The reel members themselves of the illustrated reel may be made of suitable reagent resistant materials such as, for instance, Bakelite, hard rubber or other synthetic plastics.

The embodiment of the invention illustrated in Figures 1, 2 and 3 shows the preferred relation of the axes of rotation of the two reel members. Concentric reel member 1 rotates about axis C of drive shaft 5. Eccentric reel member 2 rotates about axis E, which, as shown in Figures 2 and 3, is disposed in a plane U offset by an amount O from axis C. As shown in Figure 1, axis E is also disposed in inclined relation to axis C. The disposition of the axes C and E in offset and inclined relationship results in advance of thread lengthwise of the reel in a series of generally helical turns.

As is evident from Figure 2, rotation of the drive shaft 5 will cause concentric reel member 1 to rotate therewith. Contact of the bar members 3 of said concentric reel member with the bar members 15 of the eccentric reel member will cause said eccentric reel member to rotate about its axis E. During such rotation of each reel member about its own axis, as is apparent from Figures 2 and 3, the bar members of each reel member will project beyond the periphery defined by the bar members of the other reel member over a portion of the circumference of the reel. Consequently, thread turns wound about the reel will be carried partly by the bar members of both reel members, and, as the reel members rotate, the thread in each turn will be transferred from the bar members of one reel member to those of the other and back again.

Furthermore, due to the fact that thread starting on a rotating cylinder always travels at right angles to the axis of rotation of said cylinder, the inclined relation of the reel members shown in Figure 1 causes the thread carried by the bar members of both reel members to advance lengthwise of the reel in generally helical turns. The pitch of the helix formed by the turns; i. e., the distance that the thread will advance in one revolution of the reel, is determined by the angle of inclination X (Figure 1) between the axes C and E. For the direction of rotation indicated by the arrow in Figure 3, the thread will advance lengthwise of the reel toward the unsupported end thereof.

In both of the illustrated embodiments of the invention, the adjusting means comprises a member carried by the frame member on which the first-mentioned eccentric reel member is journaled and cooperating therewith, a rotatable in-

termediate member operating between said first-mentioned member and said frame member. By relative rotation of said intermediate member with respect to both the frame member and the member supporting the eccentric member, any desirable relation of the axes, within limits determined by the size and shape of the parts, may be obtained. Indeed, by suitably adjusting both said intermediate member and said first-mentioned member; i. e., the member supporting said eccentric reel member, the angle of inclination of the axis of the eccentric reel member with respect to that of the concentric reel member can be changed to a variety of different positions in which, however, the axis of the eccentric reel member is still disposed in the plane U.

In the embodiment of the invention illustrated in Figures 1 to 19, inclusive, the adjusting means comprises two nested sleeves 25 and 26, of which the inner sleeve 25 is mounted on frame member 6. Outer sleeve 26 is mounted on inner sleeve 25 and has rotatably mounted on it the supporting member 12 forming part of the eccentric reel member 2. The inner and outer surfaces of each sleeve comprise surfaces of revolution, being preferably cylindrical in shape. The axes of the inner and outer surfaces of each sleeve are inclined to each other.

By suitable rotation of one or both of the sleeves with respect to each other and/or with respect to the frame member 6, a wide variety of relative positions of the axes C and E can be obtained. By suitable rotation of the sleeves with respect to each other and with respect to the frame member 6, it is possible to move the axis E in a fixed plane U parallel to the axis C from a position in which there is no relative inclination of the axes C and E to one in which there is a maximum inclination, as determined by the shape of the sleeves; indeed, it is possible to reverse the direction of inclination of the axes, still keeping them in the same plane, so that for a given direction of rotation of the reel the thread can be caused to travel in the opposite direction lengthwise of the reel. The preferred shape of the sleeves 25 and 26 is shown in the drawings.

Sleeves 25 and 26 are so formed that when the adjustment means is assembled, the axes of the internal and external surfaces of both sleeves 25 and 26 intersect at a common point P which is fixed for all positions of the sleeves. The point P is preferably disposed adjacent the unsupported end of frame member 6, although it may be located at other positions. The illustrated position is desirable since the crossing point of the axes C and E of the reel members, which is determined by the point P, is at the end of the thread-bearing periphery of reel members 1 and 2.

The relation of the parts and of the various axes can be understood from Figures 4 to 7, inclusive, which show the parts adjusted so that the angle X between the axis E and the projection of the axis C on the plane U is at a maximum.

The outer surface of frame member 6 is cylindrical, terminating in a shoulder 27 spaced from the unsupported end and disposed perpendicularly to the axis A of the outer surface of frame member 6. As shown in Figures 4 to 7, inclusive, said axis A is parallel to and offset from axis C of the drive shaft; i. e., from the axis of the concentric member, by an amount O, which is the offset desired for the reel. The inner

sleeve 25 is mounted on frame member 6, being provided with an internal cylindrical bore which fits snugly but nevertheless rotatably on the external surface of frame member 6.

Sleeve 25 abuts shoulder 27 on frame member 6, being located thereagainst by one or more set screws 28 in sleeve 25 which extend into a circumferential groove 29 formed in said frame member 6. The groove 29 extends perpendicularly to the axis A of the external surface of said frame member, the end of said sleeve 25 contacting said shoulder being also perpendicular to said axis A. The external surface of sleeve 25 is of generally cylindrical form and is inclined at an angle Y to the internal bore of said sleeve, the axis B of said external surface intersecting the axis A, which is the axis of the internal bore of said sleeve 25, at P. Sleeve 25 is provided with an external shoulder 31 perpendicular to the axis B of the external surface of said sleeve.

The outer sleeve 26 is mounted on said inner sleeve 25, being provided with an inner cylindrical bore which fits snugly but nevertheless rotatably about the external surface of said inner sleeve 25. The external sleeve 26 is located endwise on inner sleeve 25 by bearing against shoulder 31 on said inner sleeve 25. The contacting end of said outer sleeve, as well as shoulder 31, is perpendicular to the axis B of the inner surface of sleeve 26. One or more set screws 32 threaded into sleeve 26 extend into a groove 33 extending around the external surface of inner sleeve 25 at right angles to the axis B, which is common to both the outer surface of inner sleeve 25 and the inner surface of outer sleeve 26.

The outer surface of sleeve 26 is of cylindrical form and is adapted to carry the supporting member 12 for eccentric reel member 2 for rotation about its axis E. The outer surface of said external sleeve 26 is so inclined to the inner bore of said sleeve that the axis E of said outer surface, which is the axis of rotation of the eccentric member 2, is inclined at an angle Z to and intersects the axis B of the inner surface of outer sleeve 26 at the point P. The sleeve 26 is provided with an external shoulder 34 perpendicular to the axis E which serves to aid in locating eccentric reel member 2 endwise. Said reel member is urged against said shoulder by the resilience of the seal 19.

In the illustrated embodiment of the invention, the angle Y between the axes of the internal and external surfaces of the inner sleeve 25 is equal to the angle Z between the axes of the internal and external surfaces of the external sleeve 26, this being preferable for reasons to be later explained. In the position illustrated in Figures 4 to 7, inclusive, sleeves 25 and 26 are so related with respect to each other and with respect to frame member 6 that the angles Y and Z lie in the common plane U. The latter passes through axis A and is offset from axis C by an amount O, being disposed parallel to said axis C at right angles to the direction in which said axis A is offset from axis C. Consequently, as shown in Figure 4, angles Y and Z add to form angle X between the axes E and A, such angle X constituting the total angle of inclination of axis E of the eccentric reel member with respect to axis C of the concentric reel member.

In the position illustrated in Figures 4 to 7, inclusive, this disposition of the axes can be obtained by rotating sleeve 25 through angle W and sleeve 26 through the angle V, from a com-

mon datum point. The latter may be taken as a point on the frame 6 lying in the plane of the axes A and C. The angle X is thus the maximum which can be obtained for the shape of the sleeves; consequently, the rate of advance of the thread along the length of the reel is at its maximum.

In the position shown in Figures 8 to 11, inclusive, the angle X between the axes of the concentric and eccentric reel members is reduced; so that the pitch of the thread on the reel is smaller than that occurring when the parts are in the relation shown in Figures 4 to 7, inclusive. In the adjustment shown in Figures 8 to 11, sleeves 25 and 26 are turned with respect to each other and with respect to the frame member 6 so that the axis B of sleeve 25 does not lie in the plane U but at an angle thereto, while sleeve 26 is turned so that its axis E does lie in the plane U. In other words, the sleeves are so turned with respect to each other that their angles do not add to form a maximum angle X, but are so related with respect to the frame member 6 that the resultant angle X lies in the desired plane U. This may be accomplished by turning the inner sleeve 25 through the angle W from the aforesaid datum point and by turning the external sleeve 26 through angle V from said datum point.

In the position of the axes illustrated in Figures 12 to 15, inclusive, the sleeves 25 and 26 are so turned with respect to each other that the axes C and E are parallel; consequently, no advance of the thread can take place. In this relationship, as shown in Figure 15, the sleeves 25 and 26 are so turned with respect to each other that they subtract; i. e., so that the thickest portion of each sleeve is in contact with the thinnest portion of the other sleeve. Thus the inclinations of the two sleeves in effect compensate, the axis E of the outer surface of the external sleeve 26 being coincident with the axis A of the internal surface of the internal sleeve 25. No matter in what position the composite sleeve formed of sleeves 25 and 26 when related as shown in Figure 15 is turned with respect to the frame member 6, the axes C and E will, of course, always be parallel because of the equal sizes of the angles Y and Z.

The position illustrated in Figures 16 to 19, inclusive, shows that sleeves 25 and 26 may be so adjusted that the angle of inclination X with respect to the frame member is in the opposite direction from that previously shown. The position shown in these figures constitutes a typical intermediate position and is similar to that shown in Figures 8 to 11, inclusive, except for the fact that the parts are so turned that the angles X, Y and Z extend in the opposite direction. That is, from the common datum point the internal sleeve 25 has been turned through the angle W in a direction opposite to the angle W shown in Figures 8 to 11, inclusive, while the external sleeve 26 has been turned to the angle V in a direction opposite to the angle V of said Figures 8 to 11.

In each of the positions illustrated, the angles W and V to which the internal and external sleeves, respectively, are turned from a common datum point are equal. This follows from the fact that the angles Y and Z between the internal and external surfaces of said sleeves are equal. If the angles Y and Z were of different sizes, it would be necessary that the angles W and V similarly be of different sizes in order to

Obtain adjustment of the axis E in the desired plane U. Of course, plane U in which it is desired to adjust axis E can itself be disposed in relationships other than that shown, even in one in which the plane passes through the axis of the concentric member C. While the reel can operate under such conditions, the best results are obtained when the plane U is disposed parallel to and perpendicular to the direction of offset from the axis C, as shown.

In the illustrated embodiment of the invention, the parts can be easily adjusted with respect to each other by reference to pointer 35 rigidly fixed to the frame member 6 in such manner as to extend over sleeves 25 and 26.

Each of said sleeves is preferably marked with the pitch of the thread turns desired, although, of course, each may be marked in fractions of an inch, number of turns per inch, or the like. In the system employed, the markings 36 are so arranged that when similar numbers on both sleeves are turned to the pointer 35, the reel is adjusted with its axis E in the plane U to give the spacing of thread turns corresponding to the selected number. Plus and minus markings may be provided, the minus markings being so arranged that when two like minus numbers are turned to pointer 35 opposite directions of inclination result, such, for instance, as that shown in Figures 16 to 19, inclusive.

The embodiment of the invention shown in Figures 20 to 22, inclusive, constitutes a modification of that above described.

In this embodiment of the invention, the inclined surfaces are not provided on curved sleeves but on flat surfaces. Member 6a is the frame member having journalled therein drive shaft 5 on which is concentrically mounted concentric reel member 1. Member 6a supports member 26a, which carries the eccentric reel member 2. As before, a collar 7 is provided on drive shaft 5 against which collar 7 concentric member 1 is held by cap nut 8. A second collar 7a is provided to bear against frame member 6a in order to aid in locating shaft 5 lengthwise.

Intermediate member 25a bears against the face 37 of frame member 6a, which face is disposed perpendicularly to the axis of rotation C of the concentric reel member. Intermediate member 25a has an opposite face 38 which is inclined to the face bearing against face 37 of frame member 6a. Supporting member 26a comprises flange portion 39, bearing against the inclined surface 38 of intermediate member 25a, and a tubular portion 41, which supports eccentric reel member 2 the axis E of which is inclined to the surface of member 26a bearing against surface 38 of member 25a.

Intermediate member 25a is rotatably mounted with respect to frame member 6a, being provided with a bore therethrough by means of which it is located on the shoulder 42 of frame member 6a. Similarly, supporting member 26a is adjustably mounted on intermediate member 25a, being located by a shoulder 43. These parts are so related that three axes intersect at a common point P; namely, (a) the axis corresponding to axis A about which member 25a is rotatably mounted on frame member 6a, which axis is perpendicular to surface 37 and offset from axis C by an amount O; (b) the axis corresponding to axis B about which the supporting member 26a is rotatably mounted on intermediate member 25a, which axis is perpendicular to surface 38; and (c) the axis E of the external surface of

tubular portion 41 about which the eccentric member 2 is journalled.

Moreover, members 25a and 26a are so formed that on member 25a the angle corresponding to angle Y of the previous embodiment between the axes corresponding to axes A and B is equal to the angle on member 26a, corresponding to angle Z of the previous embodiment, between the axes corresponding to axes B and E.

10 Consequently, the axis E can be adjusted in a common plane, which corresponds to the plane U of the previous embodiment, by suitably adjusting the members 25a and 26a with respect to each other and with respect to frame member 6a. The same method of adjustment outlined above can be performed in the present case; i. e., the angles through which the members 25a and 26a are turned with respect to a datum point on frame member 6a can be equal. The marking system can also be similar to that described above; that is, the members 25a and 26a may be so marked that when the same mark on each is turned to a pointer 35a on frame member 6a, the axis E is adjusted in the desired plane so that the thread turns are advanced in a helix having the desired pitch. Preferably, the marks on the edge of member 25a extend on the surface 38 of said member so that the corresponding marks on the edge of member 26a can be adjusted as desired.

30 In this embodiment of the invention, intermediate member 25a is held on frame member 6a by bolts 45, each of which passes through a clamping member 46 bearing on the corner of member 25a. Member 25a is, of course, accurately located by shoulder 42. Similarly, member 26a is held against member 25a by bolts 47 passing through clamps 48, being accurately located by means of shoulder 43. As shown, the edges of the front surface of each of said members 25a and 26a may be formed so that they are parallel to the rear surface of said member, thus making it simple to clamp said members against the member on which they are mounted.

45 It is apparent that in both illustrated embodiments of the invention, the adjustments can be made, if desired, without halting the operation of the reel. Thus the set screws clamping together the parts 25, 26 and 6 in the first embodiment, or the bolts clamping together parts 25a, 26a and 6a in the second embodiment, may be loosened and the parts adjusted as desired, after which the set screws or bolts may be tightened, without in any way interfering with the rotation or operation of the reel.

50 While the invention is useful in providing a simple compact adjusting means making it possible to adjust the axes to various inclined relations while maintaining them in predetermined planes, it is apparent that the adjusting means may be employed in various other manners. For instance, if it is not desired to maintain the axis in certain planes, the intermediate member may be locked or formed integral with the frame member, the external member being rotated thereabout for adjustment. Under such circumstances, of course, the adjustable axis will not be moved in a predetermined plane. It is apparent that the invention may be applied to reels of types other than that shown, being applicable in its broader aspects to the adjustment of parts other than those of thread-advancing reels.

55 It is intended that the patent shall cover, by suitable expression in the appended claims, what-

ever features of patentable novelty reside in the invention.

What is claimed is:

1. Means for adjusting the positions of the axes of rotation of two rotatable parts with respect to each other comprising a member rotatably supporting one of said parts; a sleeve mounted on said member for rotatable adjustment with respect thereto having internal and external surfaces of revolution, the axes of said internal and external surfaces being inclined to each other; and a second sleeve mounted on said first sleeve for rotatable adjustment with respect thereto having internal and external surfaces of revolution the axes of which are inclined to each other, said second sleeve rotatably supporting the other of said rotatable parts.

2. Apparatus of the character described in claim 1 in which the angles between the internal and external surfaces of both of said sleeves are equal.

3. Apparatus of the character described in claim 1 in which the axes of the internal and external surfaces of both said sleeves at all times substantially intersect in a common point.

4. Means for adjusting the positions of the axes of two cooperating rotatable parts with respect to each other comprising a first rotatable part; a member rotatably supporting said part having associated therewith a body having an external surface of revolution the axis of which is inclined to the axis of rotation of said rotatable part; a sleeve carried by said supporting member and mounted on said surface for rotary adjustment with respect to said supporting member, said sleeve having internal and external surfaces of revolution the axes of which are inclined to each other; and a second rotatable part mounted on said sleeve for rotation about the axis of the external surface of said sleeve.

5. Means for adjusting the positions of the axes of two cooperating rotatable parts with respect to each other comprising a first rotatable part; a member rotatably supporting said part having associated therewith a body having an external surface of revolution the axis of which is inclined to the axis of rotation of said rotatable part; a sleeve carried by said supporting member and mounted on said surface for rotary adjustment with respect to said supporting member, said sleeve having internal and external surfaces of revolution the axes of which are inclined to each other; and a second rotatable part rotatably supported from the external surface of said sleeve.

6. Apparatus comprising a rotatable part; a member rotatably supporting said rotatable part; a plurality of nested sleeves rotatably adjustable with respect to each other mounted on said supporting member, each of at least two of said sleeves having internal and external surfaces of revolution the axes of which are relatively inclined; and a second rotatable part rotatably supported by said sleeves.

7. Apparatus comprising a rotatable part; a member rotatably supporting said rotatable part; at least two nested sleeves rotatably adjustable with respect to each other mounted on said supporting member, each of said sleeves having internal and external surfaces of revolution the axes of which are displaced from each other; and a second rotatable part rotatably supported by said sleeves.

8. An adjustable reel comprising a first reel member; a frame member rotatably carrying said

reel member; a first eccentric sleeve adjustably mounted on said frame member; a second eccentric sleeve adjustably mounted on said first sleeve; and a second reel member rotatably carried by said second sleeve, the axis of rotation of each of said reel members being disposed within the periphery of the other reel member and the axis of said second reel member being adjustable to a variety of positions with respect to the axis of said first reel member by rotation of said sleeves with respect to each other and with respect to said frame member.

9. An adjustable reel comprising a frame member having an external surface of revolution; a sleeve mounted on said surface for rotary adjustment therewith, the internal and external surfaces of said sleeve being surfaces of revolution the axes of which are inclined to each other; a second sleeve mounted on said first sleeve for rotary adjustment therewith, the internal and external surfaces of said sleeve being surfaces of revolution the axes of which are inclined to each other; two interdigitating sets of spaced, longitudinally extending bar members each of which sets is substantially circular in cross section; means mounted on said second sleeve for rotation about the axis of the external surface of said second sleeve for supporting the bar members of one of said sets; and, rotatably carried by said frame member for rotation about an axis fixed with respect to said frame member, means for supporting the bar members of said second set.

10. Apparatus of the character described in claim 9 in which the axis of rotation of the supporting means for said second set of bar members is offset from the axis of the external surface of said frame member.

11. Apparatus of the character described in claim 9 in which the second set of bar members is concentrically mounted on a shaft journalled in said frame member.

12. Apparatus of the character described in claim 9 in which the angles between the axes of the internal and external surfaces of the two sleeves are substantially equal.

13. Apparatus of the character described in claim 9 in which the axes of the internal and external surfaces of each sleeve intersect.

14. Apparatus of the character described in claim 9 in which the axis of the external surface of said frame member and the axes of the internal and external surfaces of both of said sleeves intersect substantially at a common point.

15. An adjustable cantilever reel comprising a frame member which is supported from one end thereof only and has an external surface of revolution; a sleeve mounted on said surface of said supporting member for rotatable adjustment thereto, said sleeve having internal and external surfaces of revolution the axes of which are inclined to each other; a second sleeve mounted about said first sleeve for rotatable adjustment thereto, said second sleeve having internal and external surfaces of revolution the axes of which are inclined to each other; a set of spaced, longitudinally extending bar members which is substantially circular in cross section rotatably carried by said second sleeve; and, interleaved therewith, a second set of spaced, longitudinally extending bar members which is substantially circular in cross section rotatably carried by said frame member, the end of the structure defined by said sets of bar members

remote from said frame member being unsupported.

16. A reel comprising two interdigitating sets of spaced bar members normally rotatable about axes inclined to each other; means associated with each set of bar members for supporting the bar members thereof; a first member rotatably carrying the supporting means for one of said sets of bar members for rotation about an axis fixed with respect to said first member; a second member rotatably carrying the supporting means for the other set of bar members for rotation about an axis fixed with respect to said second member, said second member having a surface inclined to said axis of rotation; and, rotatably adjustable with respect to each of said first and second members, an intermediate member disposed between said first and second members, said intermediate member having two oppositely inclined surfaces one of which contacts the inclined surface on said second member.

17. An adjustable reel comprising a frame member having associated therewith a body having an external surface of revolution the axis of which is inclined to the axis of rotation of said reel; a sleeve, mounted about said frame member for rotary adjustment thereto, having internal and external surfaces of revolution the axes of which are inclined to each other, the internal surface of revolution of said sleeve contacting said external surface of revolution of the body associated with said frame member; two rotatable reel members, the axis of rotation of each of which is contained within the periphery of the other reel member; means rotatably carried by said sleeve from the external surface of revolution thereof for supporting one of said reel members; and, rotatably supported from said frame member, means for supporting the other reel member.

18. An adjustable cantilever reel comprising two interdigitating sets of spaced, longitudinally extending bar members, each of which is substantially circular in cross section; means associated with each of said sets of bar members for supporting the bar members thereof; a frame member rotatably carrying the supporting means for one of said sets of bar members, said frame member having associated therewith a body having an external surface of revolution which is inclined to the axis of rotation of said supporting member; and, mounted about said frame member for rotary adjustment thereto, a sleeve having internal and external surfaces of revolution the axes of which are inclined to each other, the internal surface of revolution of said sleeve contacting said external surface of revolution of the body associated with said frame member and the external surface of revolution of said sleeve rotatably carrying the supporting means for the other set of bar members, said frame member and sleeve being disposed at one end of the structure defined by said sets of bar members so as to leave the other end of said structure unsupported.

19. A reel comprising two longitudinally extending reel members, at least one of which is rotatable, normally inclined to each other and adapted to advance lengthwise of the reel in helical turns strand material wound about said reel members; a first supporting member rotatably carrying said rotatable reel member; a second supporting member carrying said other reel member, at least one of said supporting members having a surface inclined to the longitudinal axis of the reel member carried by said supporting member; and an intermediate member disposed between said first and second supporting members and rotatably adjustable with respect thereto, said intermediate member having two opposite surfaces inclined toward each other, at least one of which contacts the inclined surface on said supporting member.

20. A cantilever reel of the character described in claim 19 in which said reel members are supported at one end only from said supporting members, and in which said supporting members and intermediate member are disposed at one end only of the structure defined by said reel members, so as to leave the other end of said structure unsupported.

21. A cantilever reel comprising two interdigitating sets of bar members; means associated with each of said sets of bar members for supporting the bar members thereof; a first member carrying the supporting means for one of said sets of bar members for rotation about an axis fixed with respect to said first member; a second member carrying the supporting means for the other set of bar members for rotation about an axis fixed with respect to said second member, said second member having a surface inclined to said axis of rotation; and an intermediate member disposed between said first and second members and rotatably adjustable with respect thereto, said intermediate member having two opposite surfaces inclined toward each other, at least one of which contacts the inclined surface on said second member, said first, second and intermediate members being disposed at one end of the structure defined by said reel members so as to leave the other end of said structure unsupported.

22. An adjustable reel comprising a frame member; a plurality of nested sleeves rotatably adjustable with respect to each other and with respect to said frame member mounted on said frame member, each of at least two of said sleeves having internal and external surfaces of revolution the axes of which are inclined to each other; two interdigitating sets of spaced, longitudinally extending bar members, each of which sets is substantially circular in cross section; means rotatably carried by said sleeves for supporting the bar members of one of said sets; and, rotatably carried by said frame member for rotation about an axis fixed with respect to said frame member, means for supporting the bar members of the other of said sets.

FRED J. SAMERDYKE.
